UNITED STATES PATENT OFFICE.

WALTER SHAW, OF DEDHAM, MASSACHUSETTS, ASSIGNOR TO UNITED SHOE MACHINERY COMPANY, OF PATERSON, NEW JERSEY, A CORPORATION OF NEW JERSEY.

FASTENER-SETTING MACHINE.

1,139,449.

Specification of Letters Patent. Patented May 11, 1915.

Application filed December 9, 1912. Serial No. 735,753.

To all whom it may concern:

Be it known that I, WALTER SHAW, a citizen of the United States, and residing at Dedham, in the county of Norfolk and State 5 of Massachusetts, have invented certain Improvements in Fastener-Setting Machines, of which the following description, in connection with the accompanying drawings, is a specification, like reference characters on 10 the drawings indicating like parts in the several figures.

This invention relates to machines for setting fasteners such as eyelets in sheet material and one of its objects is to provide a machine by the use of which blind or invisible eyelets may be set in the uppers of boots and 15 shoes.

In setting blind eyelets in a shoe upper the outer part of the upper is perforated 20 and the eyelets are set in a part of the lining, or facing stay which is stitched to the lining, in register with the holes so punched. In the finished shoe, therefore, nothing is 25 visible but a series of perforations through which the lacing passes. These perforations are reinforced and kept from pulling out by the blind or invisible eyelets set in the material directly beneath them.

Heretofore blind eyeleting has been carried out by punching the eyelet holes 30 through both parts of the upper in one machine by the use of a single punch and then setting the eyelets in the lining or facing stay as a separate operation by hand or by 35 a foot power eyeleting machine. This has not in all cases proved satisfactory for it has necessitated the formation of holes in the outer leather part of the upper of diameter at least as great as the eyelet barrel, whereas 40 smaller holes would suffice for the passage of the lacing and present a more attractive appearance.

In accordance with one feature of the invention, accordingly, independent punches 45 are provided, one for punching the eyelet holes and the other for punching the holes for the lacing in the outer part of the upper.

It is believed that prior to this invention blind eyelets have never been set by a power 50 operated machine equipped with independent punching devices for operating on the lining and outer parts respectively.

Another feature of the invention consists in the provision of a thin work separating member adapted to be inserted between the 55 partially attached parts of a shoe upper and serving to separate that part which is to be punched only from that part which is to be punched and eyeleted. An important advantage of such a separating member is that 60 the two parts of the upper may be fed across its opposite faces and any desired or different operations may be performed independently without difficulty upon the parts of the work so separated. For example, as herein shown, each part is operated 65 upon by two separate tools, a punch and an independent setting die on one part and a punch and a feeding device on the other part.

In the machine herein shown an upsetting die is mounted upon one side of the work separating member and a setting die is arranged to coöperate therewith for inserting and clinching successive eyelets in the part 75 of the upper which is fed across the upsetting die. The work separating member upon its other side is made smooth so that the other side of the upper, which is to be punched only, can be fed across it without 80 obstruction.

Previously to the setting operation the part of the upper to be eyeleted is punched and, as herein shown, the other part of the upper is punched at the same time. As 85 already stated, these operations are effected by separate punches arranged to operate on the different parts.

In the embodiment of the invention herein disclosed the work separating device may 90 be utilized with good advantage as a cutting block for oppositely disposed punches, one arranged to operate on each side of a work separating member.

Another feature of the invention consists 95 in the provision of means for supporting the thin work separating member against the pressure of the setting die during the setting operation while at the same time leaving an unobstructed space for the passage of the work on both sides of the separating member between the setting operations. As herein shown this is effected by the provision of a supporting member such,

for example, as a spindle which is arranged to be moved oppositely to the setting die and to engage the smooth side of the work engaging member when the setting die is moved toward the upsetting die.

It is important in setting blind eyelets that the two parts of the upper should be fed accurately and uniformly in order that the hole punched in one part may register exactly with the eyelet set in the other part. Another feature of invention, accordingly, consists in the provision of means for positively engaging each part of the upper and moving it exactly the same distance in the feeding operation. In the embodiment of the invention herein shown this is effected by employing the two setting dies to feed that part of the upper in which the eyelets are set and by employing the supporting spindle as a feeding device for the other part of the upper. During the feeding movement, which is imparted to the work by moving the setting devices and supporting spindle laterally, the setting dies remain in engagement with the clenched eyelet while the supporting spindle remains in the hole punched in the other part of the upper.

These and other features of the invention will be best understood and appreciated from the following description of a preferred embodiment thereof selected for purposes of illustration and shown in the accompanying drawing, in which—

Figure 1 is a view in side elevation of so much of the machine as is necessary to understand the operation of its different elements; Fig. 2 is a plan view on a smaller scale than Fig. 1 of the work guiding and separating members showing a shoe upper partially supplied with blind eyelets; Figs. 3 to 5 illustrate successive steps in the operation of the machine; Fig. 6 is a sectional view of a portion of the work separating member showing the upsetting die.

The invention is herein shown as embodied in a duplex eyeleting machine of the type disclosed in Letters Patent of the United States No. 934,066, granted September 14, 1909 on an application of George Goddu. As in the machine of said patent, the forked head 10 is provided with bearings for oppositely arranged punches 14 which coöperate with a double-faced cutting block 22 set in an intermediate member 16. In the present embodiment of the invention this intermediate member has the function of a work separating device, being adapted to be slipped in between the partially attached parts of a shoe upper as shown in Fig. 2. The head 10 has also bearings for two oppositely arranged plungers 12 of which the upper one carries a setting die and spindle 13 and the lower carries a feeding and supporting spindle 34. On the

upper face of the work separating member 16 is arranged an upsetting die 23 disposed in the path of the upper plunger 12 while upon its lower side the work separating member is smooth and adapted to be engaged by the flat end of the spindle 34. The upsetting die 23 may be arranged in the work separating member in any desired manner but as herein shown it is formed on the upper surface of a removable plug, retained in position in the work separating member by a transverse screw 18 as shown in Fig. 6.

A movable raceway 36 is arranged to swing into and out of line with the spindle of the setting die and delivers successive eyelets thereto which are then inserted and clenched against the upsetting die when the plunger 12 is forced downwardly.

At one side of the work separating member 16 is disposed stationary work guiding means. This includes a hook shaped supporting plate 19 carrying yieldingly mounted presser feet 17 which act to press the work smoothly against the opposite sides of the plate 19 and direct it to the punches and the set. An edge gage 21 may also be conveniently mounted upon the plate 19. This plate is secured to and projects outwardly from a part of the machine frame, as fully shown in said patent above mentioned.

The head 10 is arranged to have movement in two directions at substantially right angles to each other and any suitable means may be employed to effect these movements, for example, the cams and levers shown in Patent No. 934,066. The first movement of the head is toward the rear for the purpose of bringing the set 12 and feeding spindle 34 into alignment with the holes in the work previously formed by the punches. The second movement is a transverse movement which draws the work toward the left (Fig. 2) and so feeds it from one eyeleting position to the next.

The punches 14 and the plungers 12 are forced toward the work separating member 16 by the levers 15 operated by cams, not shown, and are retracted by the tension springs 28 and 30 which operate on lifting levers 26 and 24. When the setting die is forced against the upsetting die in clenching an eyelet the center spindle yields inwardly within the body of the upper plunger 12. When the lower plunger is forced toward the work separating member the spindle 34 bottoms in the plunger and so rigidly supports the work separating member against the thrust of the setting die and at the same time holds the end of the plunger out of contact with the work.

The operation of the machine will be apparent from the various figures of the drawing.

A lined quarter is inserted as shown in

Fig. 2, with its outer finished part below the plate 19 and below the work separating member 16. The facing stay and lining lie above these two members. In initial position the punches and plungers occupy positions remote from the work separating member as shown in Fig. 1. The work is positioned with the point at which the first eyelet is to be set in line with the punches and the machine is thereafter started. The punches are first forced toward the opposite sides of the work separating member and both parts of the upper perforated as shown in Fig. 3. Then the punches are retracted and while the work remains at rest the head 10 is moved rearwardly bringing the setting die and spindle into line with the previously punched holes in the work. At about the same time the raceway is moved so as to carry the endmost eyelet into alignment with the center spindle of the setting die, as shown in Fig. 4. In the next step in the cycle of operations the setting die and spindle 34 are forced toward the work separating member while the raceway is withdrawn. The setting die, therefore, inserts the eyelet through the hole in the facing stay and clenches it against the upsetting die while, at the same time, the re-inforcing 30 and feeding spindle enters the hole in the part of the upper below the work separating member and engages the lower side of the member, as shown in Fig. 5. With the setting die and spindle in the same position the head is then moved transversely to feed the work and finally the die and spindle are retracted and the parts returned to initial position.

Having described my invention, I claim 40 as new and desire to secure by Letters Patent of the United States:

1. A machine for setting blind eyelets having, in combination, a thin projecting member constructed and arranged to be inserted 45 between two layers of partially attached sheet material and having an upsetting die on one side thereof, and a smooth surface on the other, means coöperating with said upsetting die for setting an eyelet in one of said layers, a punch for making the eyelet hole, and an independent punch for punching a hole through the other of said layers in alignment with the eyelet.

2. A machine for setting blind eyelets having, in combination, a thin die-carrying member having an upsetting die on one side and a surface on the other side shaped to facilitate the unimpeded passage of the material, said member projecting so that layers 50 of sheet material may be moved past both sides, means coöperating with the die to set an eyelet in the layer on one side of the member, a punch for making the eyelet hole, and a separate punch for punching a hole

through the other layer in alignment with 65 the eyelet.

3. A machine for setting blind eyelets having, in combination, a work separating device having an upsetting die on one side and a smooth surface on the other, means for 70 feeding partially attached layers of sheet material past said device in a step-by-step manner, a set for setting an eyelet in one layer in coöperation with the upsetting die, punching means for making the eyelet hole, 75 and a punch for operating on the layer which engages the smooth face of the separating device.

4. A machine for setting blind eyelets in shoe uppers, having, in combination, a projecting plate constructed and arranged to be inserted between the outer and lining parts of an upper, separate punching devices disposed on opposite sides of the plate and co-operating with the plate to punch the outer 80 and lining parts respectively, said plate having an upsetting die on one side and a smooth surface on the other, and an eyelet carrying set constructed and arranged to insert an eyelet barrel through the lining 85 part of the upper and clench it against the upsetting die on the plate while the outer part of the upper is maintained upon the other surface of the plate.

5. A machine for setting blind eyelets having, in combination, a thin work separating member constructed and arranged to be inserted between two partially attached parts of a shoe upper or the like, an upsetting die on one side of said member and on the other 100 side a surface shaped to facilitate the unimpeded passage of a shoe part, means for simultaneously punching holes in both parts in alignment with each other at one side of the upsetting die, means for relatively moving the upsetting die and the work to bring the punched hole in one part into register with the upsetting die, the other part being moved across the opposite side of the work separating member, and a set coöperating 105 with the upsetting die for inserting and clenching an eyelet in the former part.

6. A machine of the class described having, in combination, a thin projecting work separating member having an upsetting die 110 on one side, constructed and arranged to be slipped in between two partially attached parts of a shoe upper, a setting die coöperating with the upsetting die to insert and clench an eyelet in one of said parts, and a 115 supporting device arranged to be moved substantially at right angles to the work into engagement with the work separating member at a point opposite to the upsetting die to reinforce said member during the setting 120 operation.

7. A machine of the class described having, in combination, a thin work separating

device having an upsetting die on one side and a cutting bed in each side, oppositely arranged punches disposed in coöperative relation with the cutting beds, a set opposed to the upsetting die, and a square ended spindle disposed in alinement therewith upon the opposite side of the work separating member.

In testimony whereof I have signed my name to this specification in the presence of 10 two subscribing witnesses.

WALTER SHAW.
